BLAST FURNACE TUYÈRE

John H. Sprow, Jackson, Ohio

Application May 22, 1946, Serial No. 671,461

5 Claims. (Cl. 266—41)

1

My invention relates to a blast furnace tuyère. One of the objects of my invention is to provide a blast furnace tuyère which is of such a nature that it will split the air blast as it enters the tuyère so as to give an equal amount of air to each quarter area of the tuyère and will impart a twist to the air blast as it passes therethrough, thereby, producing a complete stabilizing action on the blast and concentrating the effect of the blast at the core of the tuyère. This results in a blast of air in the shape of an auger which will have a boring effect and, thereby, deeper penetration into the furnace and which will have greater maximum velocity and better velocity concentration at a given distance from the tuyère and results in a more evenly distributed air blast.

Another object of my invention is to provide a blast furnace tuyère of the type indicated above which is of such construction that a bar may be passed therethrough during operation of the furnace to clean out deposits of cinders which might form in the tuyère or to break up pilasters if they form inside the furnace adjacent the tuyère.

Other objects will be apparent hereinafter.

The preferred embodiment of my invention is illustrated in the accompanying drawings wherein:

Figure 1 is an elevational view of my tuyère taken at the intake end thereof.

Figure 2 is a longitudinal sectional view taken substantially along line 2—2 of Figure 1.

Figure 3 is a transverse sectional view through the tuyère taken substantially at the location of line 3—3 on Figure 2.

Figure 4 is a perspective view of a portion of the tuyère showing the inside thereof.

Figure 5 is a horizontal sectional view taken along line 5—5 of Figure 6 through a blast furnace provided with a series of my tuyères showing the action of the tuyères.

Figure 6 is a vertical sectional view taken along line 6—6 of Figure 5.

With reference to the drawings, I have shown my tuyère as comprising a substantially frusto-conical hollow body 1. This body 1 is provided with a surrounding water jacket 2 provided with inlet and outlet openings 3 and 4. The body 1 is provided with an axial bore 5 for receiving the air blast and extending entirely therethrough from the inlet end 6 to the nose or outlet end 7. The wall or surface of the bore 5 is gradually tapered from the inlet end to the outlet end of the tuyère body 1. The inlet end 6 is provided with an outwardly flared surface 8 leading into the bore 5.

At the inlet end of the tuyère body 1, I provide a series of integral radially projecting ribs 9 which are spaced circumferentially on the surface of the bore 5 at intervals of 90°. Each rib 9 includes a straight section 10 which extends from the inner extremity of flared surface 8 a short distance towards the nose end of the tuyère body 1. These straight sections 10 have inner edges 11 substantially parallel to the longitudinal axis of the tuyère body. Each rib 9 also includes a helicoid section 12 which extends from the inner end of straight section 10 to a point slightly beyond the mid-point of the length of the tuyère body 1. The sections 12 and sections 10 are in angular relationship. The helicoid sections 12 have one-eighth of a turn from the inner ends of straight sections 10 in their inner extremities and, consequently, the inner extremity of each helicoid section 12 is spaced circumferentially on the surface of bore 5 from the outer extremity thereof through an angle of 45°. Furthermore, each of the helicoid sections 12 is twisted about its own center line.

A second series of integral radially projecting ribs 15 extend from the inner extremities of ribs 9 to the nose of the tuyère or outlet end 7 of the bore 5. These ribs 15 are identical with the ribs 9 except they are not provided with straight sections corresponding to sections 10 of ribs 9. They are of helicoid form and have one-eighth of a turn from their inner ends to their outer ends similar to helicoid sections 12. They are also twisted about their own axes like sections 12. The helicoid ribs 15 are not in alignment with sections 12 but are disposed circumferentially between them. The helicoid ribs 15 are spaced circumferentially from each other on the surface of bore 5 90° apart but are spaced only 45° from the adjacent helicoid sections 12 of ribs 9.

In the operation of the tuyère, as shown in Figures 5 and 6, the air blast entering into the inlet end 6 of bore 5 is first split into four sections by the straight sections 10 of ribs 9, as it is initially being compressed by the taper of the bore. Thus, the air is divided into four equal parts around the tuyère. It has a short straight travel before coming into contact with the helicoid sections 12 of the ribs 9. When the blast does come into contact with the sections 12, it is twisted. The twisting action is continued and the air blast is further split when it comes into contact with the helicoid ribs 15. As the blast leaves the outlet end 7 of bore 5 and enters the furnace, it is rotated, as illustrated in Figure 5.

Thus, the blast of air is first split into four equal parts and then twisted by the first set of

ribs. Then it comes into contact with the second set of ribs which further split it and twist it. This produces a blast which is rotated as it leaves the tuyère and enters the furnace. Due to the helicoid sections of the ribs and also to the fact that they are twisted about their own axes, the air blast will be in the shape of an auger when it enters the furnace and will have a boring effect that gives a deeper penetration into the raw materials of the tuyère zone. By passing through my tuyère the blast is stabilized and concentrated at the core of the tuyère. This not only results in a deeper penetration into the furnace, but gives greater velocity to the blast, and results in better velocity concentration at a proper distance from the tuyère and in a more evenly distributed air blast. Because the ribs 9 are staggered relative to the ribs 15, a clean out bar can be passed through the bore 5 along the surface thereof through the space between the adjacent ribs 9 and 15. Thus, cinders or other deposits can be removed from the wall of bore 5 or pilasters inside the furnace can be broken up.

The helicoid ribs in the tuyère can curve in either direction and can be of different sizes. Furthermore, the number thereof can be varied.

It will be apparent that I have provided a tuyère having a number of advantages. Some of the important advantages have been discussed and others will be apparent.

Having thus described my invention, what I claim is:

1. A tuyère comprising a body portion having a bore extending therethrough, a series of helicoid ribs projecting radially inwardly from the surface of said bore and extending a portion of the length of the bore, and a second series of helicoid ribs projecting radially inwardly from the surface of said bore and extending along a portion of the length of the bore, said ribs of the first series being staggered relative to the ribs of the second series so as to provide clear paths longitudinally of said surface of the bore to facilitate cleaning by means of a bar or the like inserted in the bore and passed along such sur-

face substantially in the same plane as the axis of the bore.

2. A blast furnace tuyère comprising a body having a bore of circular cross-section with a surface tapering inwardly towards the axis of the body from the inlet end to the outlet end, a series of helicoid ribs projecting inwardly from the surface of said bore and extending from a point adjacent the inlet end to a point intermediate the length of the bore, said ribs being spaced from each other circumferentially of the bore, and a second series of helicoid ribs projecting inwardly from the surface of said bore and extending from a point adjacent the inner ends of the ribs of the first series to a point adjacent the outlet end of the bore, said ribs of the second series being spaced from each other circumferentially of the bore and being staggered relative to the ribs of the first series so as to provide clear paths longitudinally of said surface of the bore to facilitate cleaning by means of a bar or the like inserted in the bore and passed along such surface substantially in the same plane as the axis of the bore.

3. A tuyère according to claim 2 wherein straight blade sections are provided on the first series of ribs at the inlet end of the bore.

4. A tuyère according to claim 2 wherein the helicoid ribs of both series have one-eighth of a turn.

5. A tuyère according to claim 2 wherein the helicoid ribs of both series have one-eighth of a turn and are twisted about their own axes.
